MERCURY ARC CONVERTER

David Henry Donaldson, North Wembley, and
 Henry Thomas Ramsay, Hatch End, Pinner,
 England, assignors to The General Electric
 Company Limited, London, England

Application May 13, 1940, Serial No. 334,808
 In Great Britain May 15, 1939

18 Claims. (Cl. 175—354)

This invention relates to an improvement in or modification of mercury arc converters of the type wherein a discharge occurs within a discharge envelope along an arc from an anode to a mercury pool cathode, and, for initiating said discharge, means are provided for causing a stream of mercury to issue from an orifice as a continuous jet impinging on an electrode within the discharge envelope, for causing an electric current to flow along said jet, and for breaking said jet under the influence of an electric signal while said jet current is flowing.

The essential feature of such converters is that they comprise means for causing a stream of mercury to issue from an orifice within the envelope of the converter, normally as a continuous jet impinging on an electrode, and comprise, or are adapted to be associated with, means for causing an electric current to flow along the said jet and means for breaking the said jet under the influence of an electric signal.

Previously it was thought that, in order that a current may be caused to flow as aforesaid, the source from which the said stream flows must be so far insulated from the said electrode that the impedance of the said jet is less, or not much greater than, the impedance between the said source and the said electrode.

We have now realised that it is not necessary that the source should be insulated in the sense that there is a minimum permissible resistance between the source and the electrode. For an E. M. F. can be generated by magnetic induction in a circuit that has substantially zero resistance; but it is necessary, in order that a finite E. M. F. should be generated, that the circuit should have a finite impedance at the frequency of the inducing field.

Thus, as shown in the accompanying drawing, 1 is the mercury cathode, 2 the anode, 3 the circuit providing the main discharge current, 4 the orifice from which the jet 5 issues and which is joined to the cathode by a channel 6 of very low resistance, consisting of a tube 7 through which the mercury is driven by the pump 8. A few turns 9 of the channel are linked with the magnetic core 10, with which is also linked a primary winding 11, so that the turns 9, the core 10, and the winding 11 form a transformer. The ends of the winding 11 are connected with a D. C. supply 12 through an interrupter 13. When intermittent current is caused to flow in the primary 11 by the operation of the interrupter 13, current will also flow in the path 6, so long as the jet is unbroken. The source 12 and interrupter 55

13 may obviously be replaced by an A. C. source the frequency and phase of which are suitably related to those of the main circuit 3.

Conductance along the channel 6 may be provided mainly or wholly by the mercury in the channel; but this is not necessary; if the conductance lay mainly in the walls of the channel, the current driven by the E. M. F. induced in the turn 9 would flow through the jet, where the walls necessarily have a gap, although little would flow through the mercury in the channel.

According to the invention, in a mercury arc converter of the type specified, the said means for causing a current to flow along the said jet 15 comprises a conducting channel along which the mercury flows between the said orifice and the said electrode, a transformer of which the said channel is the secondary, and means for causing an alternating or intermittent current to flow in the primary of the said transformer.

It is known that the jet may be broken by the pinch effect. By the "pinch effect" is meant the well known tendency of a conductor traversed by an electric current to contract, and to 25 become of smaller cross-section, under the electrodynamic forces generated by the mutual reaction of the elements of the said current. But we have found that the jet may be broken by causing a current to flow through it even when 30 the strength of this current is too small to break the jet by the pinch effect proper. Indeed if, in the arrangement shown in the said drawing, an impulsive voltage, lasting only a small fraction of the period of the main supply 3, is applied to 35 the primary 11, so that a pulse of current flows in the path 6 followed by a longer interval during which the current is much less than it is during the pulse, the jet may be interrupted and the main discharge initiated after the said pulse of 40 current has ceased, and during the said longer interval. The explanation is probably that the pulse starts a mechanical disturbance in the jet which leads to its instability, just as tapping the orifice might. Since a break in the jet will start 45 the main discharge, even when the current flowing in the jet is quite small, it is possible by using this fact to start the main discharge by starting suddenly in the jet a current too small, or enduring for too short a time, to break the jet by the 50 pinch effect.

According to a subsidiary feature of the invention, the said means for breaking the jet are means for starting in it suddenly a current too small to break the jet by the pinch effect.

The means for thus breaking the jet may be

independent of the means for maintaining a current through it at the instant when it is broken. Thus, in the said drawing, the primary 11 might be fed from the supply 3 so that the current induced in the jet by this winding varies but slowly. An impulsive current, sufficient to set up the mechanical disturbance that breaks the jet, might then be provided by other means, for example another winding on the core 10 or by connecting suddenly a charged condenser across the secondary winding 8.

The jet may also be broken by other means. Thus, the jet may be permanently subjected to a transverse magnetic field and broken by the lateral force due to a current through it; the current caused to flow along the jet may then be the electrical signal. Conversely, a constant current may be passed along it, and a transverse magnetic field established at the appropriate point in the cycle. Other methods will occur to those skilled in the art. Whether the current which is caused to flow in the primary 11 be an intermittent current, an alternating current or an impulsive current, it is of a fluctuating nature and is defined as "fluctuating" in the annexed claims.

We claim:

1. In a mercury arc converter of the type wherein a discharge occurs within a discharge envelope along an arc from an anode to a mercury pool cathode, means for initiating said discharge by causing a stream of mercury to flow along a conducting channel and to issue from an orifice therein as a continuous jet impinging on said cathode, by causing a fluctuating current to flow in the primary of a transformer of which said channel is the secondary, thereby causing an electric current to flow along said jet, and by breaking said jet under the influence of an electric signal while said jet current is flowing.

2. In a mercury arc converter of the type wherein a discharge occurs within a discharge envelope along an arc from an anode to a mercury pool cathode, means for initiating said discharge by causing a stream of mercury to flow along a conducting channel and to issue from an orifice therein as a continuous jet impinging on said cathode, by causing a fluctuating current to flow in the primary of a transformer of which said channel is the secondary, thereby causing an electric current to flow along said jet, and by breaking said jet under the influence of an electric signal while said jet current is flowing by starting in it suddenly a current which, in itself, is insufficient to contract the jet, under the electrodynamic forces generated by the mutual reaction of the elements of said current, to such cross-section as to cause said jet to break.

3. In a mercury arc converter of the type wherein a discharge occurs within a discharge envelope along an arc from an anode to a mercury pool cathode, means for initiating said discharge by causing a stream of mercury to flow along a conducting channel and to issue from an orifice therein as a continuous jet impinging on said cathode, by causing a fluctuating current to flow in the primary of a transformer of which said channel is the secondary, thereby causing an electric current to flow along said jet, and by breaking said jet under the influence of an electric signal while said jet current is flowing by starting in it suddenly a current which is independent of the current maintained through the jet at the instant when it is broken and which, in itself, is insufficient to contract the jet, under

the electro-dynamic forces generated by the mutual reaction of the elements of said current, to such cross-section as to cause said jet to break.

4. In a mercury arc converter of the type wherein a discharge occurs within a discharge envelope along an arc from an anode to a mercury pool cathode, means for initiating said discharge by causing a stream of mercury to flow along a conducting channel and to issue from an orifice therein as a continuous jet impinging on said cathode, by causing a fluctuating current to flow in the primary of a transformer of which said channel is the secondary, thereby causing an electric current to flow along said jet, and by breaking said jet under the influence of an electric signal while said jet current is flowing by permanently subjecting said jet to a transverse magnetic field and breaking it by the lateral force due to a current through it.

5. In a mercury arc converter of the type wherein a discharge occurs within a discharge envelope along an arc from an anode to a mercury pool cathode, means for initiating said discharge by causing a stream of mercury to flow along a conducting channel and to issue from an orifice therein as a continuous jet impinging on said cathode, by causing a fluctuating current to flow in the primary of a transformer of which said channel is the secondary, thereby causing an electric current to flow along said jet, and by breaking said jet under the influence of an electric signal while said jet current is flowing by passing a constant current along said jet and establishing a transverse magnetic field at the appropriate point in the cycle.

6. In a mercury arc converter of the type wherein a discharge occurs within a discharge envelope along an arc from an anode to a mercury pool cathode, means for initiating said discharge comprising a conducting channel for a stream of mercury, said channel being formed with an orifice through which mercury issues as a continuous jet and impinges on said cathode, a transformer of which said channel is the secondary and with the primary of which is connected a source of fluctuating electric current whereby an induced current is caused to flow along said jet between said orifice and said cathode, and means for breaking said jet under the influence of an electric signal while said jet current is flowing.

7. In a mercury arc converter of the type wherein a discharge occurs within a discharge envelope along an arc from an anode to a mercury pool cathode, means for initiating said discharge comprising a conducting channel for a stream of mercury, said channel being formed with an orifice through which mercury issues as a continuous jet and impinges on said cathode, a transformer of which said channel is the secondary and with the primary of which is connected a source of fluctuating electric current whereby an induced current is caused to flow along said jet between said orifice and said cathode, and means for breaking said jet under the influence of an electric signal while said jet current is flowing by suddenly starting in said jet current a current which, in itself, is insufficient to contract the jet, under the electrodynamic forces generated by the mutual reaction of the elements of said current, to such cross-section as to cause said jet to break.

8. In a mercury arc converter of the type wherein a discharge occurs within a discharge envelope along an arc from an anode to a mercury pool cathode, means for initiating said discharge comprising a conducting channel for a stream of

mercury, said channel being formed with an orifice through which mercury issues as a continuous jet and impinges on said cathode, a transformer of which said channel is the secondary and with the primary of which is connected a source of fluctuating electric current whereby an induced current is caused to flow along said jet between said orifice and said cathode, and means for breaking said jet under the influence of an electric signal while said jet current is flowing by suddenly starting in said jet current a current which is independent of the current maintained through the jet at the instant when it is broken and which, in itself, is insufficient to contract the jet, under the electrodynamic forces generated by the mutual reaction of the elements of said current, to such cross section as to cause said jet to break.

9. In a mercury arc converter of the type wherein a discharge occurs within a discharge envelope along an arc from an anode to a mercury pool cathode, means for initiating said discharge comprising a conducting channel for a stream of mercury, said channel being formed with an orifice through which mercury issues as a continuous jet and impinges on said cathode, a transformer of which said channel is the secondary and with the primary of which is connected a source of fluctuating electric current whereby an induced current is caused to flow along said jet between said orifice and said cathode, and means for breaking said jet under the influence of an electric signal while said jet current is flowing by permanently subjecting said jet to a transverse magnetic field and breaking it by the lateral force due to a current through it.

10. In a mercury arc converter of the type wherein a discharge occurs within a discharge envelope along an arc from an anode to a mercury pool cathode, means for initiating said discharge comprising a conducting channel for a stream of mercury, said channel being formed with an orifice through which mercury issues as a continuous jet and impinges on said cathode, a transformer of which said channel is the secondary and with the primary of which is connected a source of fluctuating electric current whereby an induced current is caused to flow along said jet between said orifice and said cathode, and means for breaking said jet under the influence of an electric signal while said jet current is flowing by passing a constant current along said jet and establishing a transverse magnetic field at the appropriate point in the cycle.

11. In a mercury arc converter of the type wherein a discharge occurs within a discharge envelope along an arc from an anode to a mercury pool cathode, means for initiating said discharge, said means comprising the combination of means for causing a stream of mercury to flow along a predetermined path and to issue from an orifice as a continuous jet impinging on an electrode within the discharge envelope; inductive means for causing an electric current to flow along said jet, said last named means including a portion of said path; and means for breaking said jet under the influence of an electric signal while the jet current is flowing.

12. In a mercury arc converter of the type wherein a discharge occurs within a discharge envelope along an arc from an anode to a mercury pool cathode, means for initiating said discharge, said means comprising the combination of means for causing a stream of mercury to flow along a predetermined path and to issue from

an orifice as a continuous jet impinging on an electrode within the discharge envelope; inductive means for causing an electric current to flow along said jet, said last named means including a portion of said path; and means for breaking said jet while said jet current is flowing under the influence of an electric signal during successive cycles of the alternating current rectified by said converter so as to initiate a discharge in each of said cycles.

13. In a mercury arc converter of the type wherein a discharge occurs within a discharge envelope along an arc from an anode to a mercury pool cathode, means for initiating said discharge, said means comprising the combination of means for causing a stream of mercury to flow along a predetermined path and to issue from an orifice as a continuous jet impinging on an electrode within the discharge envelope; and inductive means for passing a large fluctuating current through said jet during successive cycles of the alternating current rectified by said converter so as to break said jet while said impulsive jet current is flowing and thereby initiate a discharge between the said anode and said cathode of said device in each of said cycles, said last named means including a portion of said path.

14. In a mercury arc converter of the type wherein a discharge occurs at regular temporal intervals along an arc from an anode to a mercury pool cathode, means for initiating said discharge at each of said intervals, said means comprising the combination of an orifice; means for causing a jet of mercury to flow along a predetermined path and to issue continuously from said orifice; inductive means for causing an electric current to flow along said jet, said last named means including a portion of said path; and means for breaking said jet at each of said intervals while said jet current is flowing.

15. In a mercury arc converter of the type wherein a discharge occurs at regular temporal intervals along an arc from an anode to a mercury pool cathode, means for initiating said discharge at each of said intervals, said means comprising the combination of an orifice; means for causing a jet of mercury to flow along a predetermined path and to issue continuously from said orifice; inductive means for causing an electric current to flow along said jet, said last named means including a looped portion of said path and a coupled inductance; and means for breaking said jet at each of said intervals while said jet current is flowing.

16. In a mercury arc converter of the type wherein a discharge occurs at regular temporal intervals along an arc from an anode to a mercury pool cathode, means for initiating said discharge at each of said intervals, said means comprising the combination of an orifice spaced apart from said cathode pool; means for causing a jet of mercury to flow along a predetermined path and to issue continuously from said orifice and impinge said cathode pool; inductive means for causing an auxiliary electric current to flow along said jet, said last named means including a portion of said path; and means for breaking said jet at each of said intervals while said jet current is flowing.

17. In a mercury arc converter of the type wherein a discharge occurs within a discharge envelope along an arc from an anode to a mercury pool cathode, means for initiating said discharge, said means comprising the combination of a channel; an orifice in said channel; means

for causing a stream of mercury to flow along said channel and to issue from said orifice as a continuous jet impinging on an electrode within the discharge envelope; inductive means, including a portion of said channel, to cause an electric current to flow along said stream and said jet; and means to break said jet while said current is flowing.

18. In a mercury arc converter of the type wherein a discharge occurs within a discharge envelope along an arc from an anode to a mercury pool cathode, means for initiating said discharge, said means comprising the combination

5 of a channel; an orifice in said channel; means for causing a stream of mercury to flow along said channel and to issue from said orifice as a continuous jet impinging on an electrode within the discharge envelope; an inductance coupled with said stream; and means to pass a fluctuating electric current through said inductance whereby a fluctuating, induced electric current is caused to flow along said stream and said jet and to cyclically break said jet.
